UNITED STATES PATENT OFFICE.

SPENCER D. EARL, OF PHILADELPHIA, PENNSYLVANIA.

SPRING-ACTUATED FIRE INDICATOR OR ALARM.

SPECIFICATION forming part of Letters Patent No. 424,545, dated April 1, 1890.

Application filed April 8, 1889. Serial No. 306,300. (No model.)

To all whom it may concern:

Be it known that I, SPENCER D. EARL, a citizen of the United States, residing at the city of Philadelphia, in the county of Philadelphia and State of Pennsylvania, have invented certain new and useful Improvements 5 in Spring-Actuated Fire Indicators or Alarms, of which the following is a specification.

My invention relates to apparatus for indicating an alarm in buildings in the event of fire occasioned by overheated stoves, furnaces, or other causes.

The principal object of my invention is to provide an alarm of comparatively simple 15 construction and of positive action for indicating or signaling to the occupants of the building of fires, occasioned as they are so generally by sparks from stoves, overheated furnaces, and defective flues.

My invention consists in providing a fire-alarm indicator actuated by a spring mechanism of a positive character in contradistinction to apparatus of the type as heretofore constructed, in which the same has been 20 dependent on the making or breaking of an electric circuit or circuits by the heat evolved from the burning floors, beams, or other parts of the building consuming a strip or strips of fusible metal or by setting in action a mercurial thermometer arranged in the circuit of 25 a battery of the apparatus for actuating an alarm or bell.

The nature and characteristic features of my invention will be more fully understood, 30 taken in connection with the accompanying drawings, forming part hereof, and in which—

Figure 1 is a front elevation of the three floors of a building, showing my invention in application to the respective floors thereof. 35 Fig. 2 is a side elevation of the spring-actuated alarm apparatus, showing the mechanism for actuating the bell. Fig. 3 is a top or plan view of the spring-actuated mechanism of the apparatus. Fig. 4 is a side view of a section 40 of tarred rope with pendent fibrous threads to be located in proximity to the furnaces or stoves of the building, and said material being made of or coated with a readily-ignitable substance; and Fig. 5 is a perspective view of 45 a floor having a series of grooves running at right angles to each other, in which are mounted the ignitable rope or threads connected

with the spring-actuated mechanism of the alarm.

Referring to the drawings, A is the frame-work or housing for the spring-actuated mechanism. To this housing is mounted a shaft B, around which is coiled a flat spring C, secured to said shaft B at one extremity thereof, and its opposite extremity secured to 55 an arm d, which is secured to a gear-wheel D, mounted upon said shaft. This gear-wheel D meshes with a pinion d', mounted on a shaft d'. The pinion d' is formed integral with or secured to a gear-wheel E, which meshes 60 with a pinion F, mounted on the shaft f, which is journaled to the housing A. This pinion F carries or operates an escape-wheel G, with which engages wedge-pallets g, secured to a shaft g', the journals of which 65 are loosely mounted in the housing A. This shaft g' carries a vertical T-shaped arm h, provided at each of the upper ends thereof with knobs h' and h'' for actuating the bell I, supported from the side of the housing A by 70 means of a vertically-curved arm i'. On the shaft B, upon which is mounted the coiled mainspring C for storing up the power for actuating the combined mechanism, is mounted a ratchet-wheel c', which is held rigidly 75 on the shaft B. With the teeth of this ratchet-wheel c' engages a pawl c'', which is pivoted to the housing A, and this pawl is held in engagement with the teeth of said ratchet-wheel c' by means of a flat spring c'', secured 80 to the housing A. The shaft B is formed square at its outer extremity, in order that a key may be readily applied thereto for winding or storing up the power for actuating the 85 combined mechanism in the flat spring C, 90 coiled around the shaft B. In the upper part of the housing A is loosely mounted a shaft k with a crank n. The shaft k is held in operative position in the housing A by means of the washers k' and k'', which are held to 95 place by means of pins k''' and k''. On the shaft k is mounted a sector or arm L, the upper portion of which is provided with an opening, into which one end of a spiral spring l is secured, and the opposite end of said 100 spring is attached to a projecting pin m, located adjacent to the housing A. The sector or arm L performs the function of arresting the train of gearing and the teeth of this sec-

tor-arm engage with the teeth of the gear-wheel E, and the same is kept in position by means of the crank n, the wire n', the bell-crank lever O, rope p, and ignitable material or 5 rope R, rope S, and the weight T, which equalize the force of the spring C of the alarm mechanism.

If from any cause the above-mentioned connection be broken, the weight T will drop 10 to the floor of the building, thereby causing the spring C to be brought into action to impart motion to said train of gearing and said scape-wheel G, which imparts motion to the hammer h, to actuate the bell I, to give the 15 desired alarm to the occupants of the house of the impending danger confronting them.

In the lower extremity of the crank n is inserted a wire n', the opposite extremity of which may be formed with an eye n², and 20 made to engage with a bell-crank lever O, pivoted at o' to a block o², secured to the wall of the apartment or room. Near the outer extremity of this bell-crank lever is provided a hook o³, to which is attached a spiral spring 25 o⁴ for maintaining the bell-crank lever O in proper position when the combined apparatus is set. To the extreme end of the bell-crank lever O is attached a wire p, running therefrom over pulleys to the point or parts 30 of the building where fire is likely to originate, where connections are made with a rope or ropes R, made of a material or materials capable of being readily ignited or coated with rosin, tar, or other readily-ignitable substance 35 or substances. These ropes or materials are disposed through the internal spaces of the walls in proximity to the flues of the building or around about the fire-places of the different apartments of the building and run along 40 through grooves r and r' in the beams or floors r² of the several apartments, where they are again connected with wires S, running over pulleys, suitably arranged in the walls, to the cellar. The wires S therein are then joined 45 to the readily-ignitable materials or ropes R, with pendants located above the furnace or around about the same or in such positions thereto as wherever the most danger is to be apprehended, and from which materials so 50 disposed wires are again run therefrom over a pulley or pulleys to a weight or weights T.

The principal advantages of my invention are, first, that the apparatus is positive in action, being not dependent upon the fusing of 55 strips of metal or the setting into action at a high temperature of a mercurial thermometer arranged in an electric circuit for giving an alarm in case of fire; but, aside from this fact, the principal objection heretofore experienced in the use of such apparatus has been that the different portions of the building could not well be reached—that is, a fire originating from sparks or overheated stoves or furnaces might consume a large portion of 60 the building before heating up the fusible

strips of metal or setting into action the mercurial thermometer, so as to effect the apparatus, while by my arrangement of apparatus, with the readily-ignitable material disposed along the floors and beams in the different fire-originating spots or parts of the building, with the pendent threads or cords of ignitable material or coated with substances or materials capable of being readily ignited in most any direction or part of the building that a fire 70 might originate, this ignitable material or materials, preferably in the form of ropes or cords R, will be consumed, thereby operating the spring-actuated mechanism of the device by setting off the bell or alarm in the following manner: The mainspring C is wound up by means of a key or crank and the sector or arm L brought into engagement with the gear-wheel E. Connections are then made between the spring-actuated mechanism and the weight 85 T, counterbalancing the power of the spring C. With special reference, now, to Fig. 1, the sector or arm L is kept in position to arrest the train of gearing by the crank n, wire n', substance or material R in the grooves r and r' of the third floor of the building; thence the wire or rope is conducted in any preferred manner along the second floor to a bell-crank lever O, over a pulley, and through a webbing 90 of ignitable material provided with pendants, and which webbing may be located above the stove or furnace, from which it passes over a pulley to a weight T to counterbalance the stored-up power or energy in the spring C. 100

If the above connection should be broken, either through fire or an overheated stove or furnace, thereby severing the rope or ignitable material or substance R, the weight T will drop, freeing the sector or arm L and causing 105 the spring C to actuate the hammer h to operate the bell I by means of the train of gearing and scape-wheel G. The spring o', attached to the bell-crank lever O, operates to draw the freed ends of the rope or other ignitable material R in the direction of the spring-actuated mechanism hereinabove described, and thereby insures a release of the sector or arm L to obtain the alarm desired and apprise the occupants of the building of 110 the impending danger confronting them. The spring-actuated mechanism may be constructed so that the alarm is given for an indefinite period of time by increasing the storage capacity of the mainspring C, mounted 115 on and coiled around the shaft B.

Having thus described the nature and objects of my invention, what I claim as new, and desire to secure by Letters Patent, is—

The combination, with the spring-actuated 125 device for giving an alarm, as described, of a crank with a toothed sector or arm engaging with the main gear-wheel of said device, a wire or rope connected with said crank and a bell-crank lever, a wire or wires attached to a 130

rope or ropes of ignitable material from said
bell-crank lever and disposed through the
building as described, and said rope or ropes
having ignitable pendants attached thereto,
5 and a wire or wires leading from and con-
nected with a weight or weights, all arranged
as shown, and for the purposes set forth.

In witness whereof I have hereunto set my
signature in the presence of two subscribing
witnesses.

SPENCER D. EARL.
